UNITED STATES PATENT OFFICE.

EGBERT CORNELIUS AND BURTON G. COPE, OF ORRVILLE, OHIO.

BLAST-LOADING DEVICE.

No. 796,192.

Specification of Letters Patent.

Patented Aug. 1, 1905.

Application filed July 8, 1904. Serial No. 215,714.

To all whom it may concern:

Be it known that we, EGBERT CORNELIUS and BURTON G. COPE, citizens of the United States, residing at Orrville, in the county of Wayne and State of Ohio, have jointly invented certain new and useful Improvements in Blast-Loading Devices; and we do hereby declare that the following is a full, clear, and exact description of the same, reference being had to the annexed drawings, and to the figures of reference marked thereon, in which—

Figure 1 is a sectional view of the funnel, showing the same properly attached to the top or upper end of the feed-tube, showing the valve properly located and mechanism for operating the valve. Fig. 2 is a detached view of the combined gage and wire-holder. Fig. 3 is a view showing a number of sections of the feed-tube and the different parts properly arranged with reference to each other. Fig. 4 is a detached view showing a portion of the slotted or open blasting-material-delivery section. Fig. 5 is a detached view of the tamping-plug. Fig. 6 is a detached view of a portion of one section of a feed-tube. Fig. 7 is a detached view of one of the section-couplings. Fig. 8 is a view of the explosive holder.

The present invention has relation to blast-loading devices especially designed to convey the blasting material to the place or point where it is to be exploded; and it consists in the novel arrangement hereinafter described, and particularly pointed out in the claims.

Similar numerals of reference indicate corresponding parts in all the figures of the drawings.

In the accompanying drawings, 1 represents the feed-tube, which is preferably formed in sections, and the sections connected together by means of the couplings 2, by which arrangement a feed-tube of any desired length or of various lengths may be produced, as it will be understood that the number of sections may be increased or decreased, owing to the different depths of the drill-holes.

For the purpose of providing a means for feeding blasting - powder into the feed-tube proper the funnel 3 is provided, which funnel is provided with the downward - extending flange 4, which flange embraces the top or upper end of the feed-tube 1, as illustrated in Figs. 1 and 3.

For the purpose of supporting the funnel the flange 4 is provided with the rib 5, located upon the inner periphery of the tube 4, and

is so arranged that said rib will rest upon the top end of the tube 1.

The funnel 3 is provided with the valve 6, which valve consists of a ball formed of a size to close the lower end of the funnel 3, and for the purpose of opening the funnel, so as to allow blasting material to enter the tube 1 and be conveyed through the tube, the valve 6 is provided with the arm 7, which arm is pivotally connected to the flange 8 or its equivalent, and for the purpose of holding the valve in an elevated position the spring-catch 9 is provided.

To the bottom or lower end of the feed-tube 1 is attached the delivery-section 10, which delivery-section is provided with the slot or opening 11.

The delivery-section 10 is formed of brass or like material or of such material that will not strike fire by coming in direct contact with the explosive material.

It will be understood that brass or like material will not cause an explosion of powder by coming in contact therewith, and hence the necessity of employing brass or like material for the explosive-delivery section.

To the bottom or lower end of the delivery-section 10 is attached the tamping-plug 12, which tamping-plug is preferably formed of wood or other fibrous material.

For the purpose of shunting the blasting material so that it will pass through the opening 11 the top or upper end of the tamping-plug 12 is tapered substantially as illustrated in the drawings.

In use the various sections of the feed-tube are connected together so as to produce a tube of the desired length, the lower section being provided with the tube 10 and the plug 12, the tube, together with these parts, being lowered into the drill-hole, by which arrangement the blasting material is conveyed through the tube without coming in contact with the surface of the drill-hole until it reaches the opening 11, which opening is located just above the point where the blasting material is to be deposited, thereby preventing any choking or clogging of the blasting material during the time it is conveyed to the bottom of the drill-hole.

It will be understood that during the time powder is conveyed to the bottom of the hole the feed-tube sections, together with the tamping-plug, may be given a reciprocating movement by hand or otherwise, thereby tamping the powder, it being understood that the pow-

the holder 13, to be with-
is provided with the slot
pen at its bottom or lower

For the purpose of connecting the tamping-
plug 12 to the bottom or lower end of the de-
livery-tube 10 the pin 17 is provided, which
pin is preferably formed of wood.

The delivery-tube 10 is shown provided
with a single slot or opening.

It will be understood that the number of
openings may be increased, if it is desired—
that is to say, that an opening may be formed
in the tube opposite from that shown in the
drawings.

The gage and holder 15 consists of a spring-
band provided with flanges 18, which spring-
band is clamped upon the upper tube-section
by means of the thumb-screw 19 and the
hooked flange 20.

Having fully described our invention, what
we claim as new, and desire to secure by Letters Patent, is—

1. In a blast-loading device, the combina-
tion of a feed-tube, a delivery-tube connected
thereto, and a tamping-plug located directly
below the delivery-tube and an explosive-
holder adapted to be attached to the tamping-
plug, substantially as and for the purpose
specified.

2. In a blast-loading device, a tube and a
funnel connected thereto, said funnel provided
with a valve, explosive-wires and a hook
adapted to hold said explosive-wires, said
hook carried by the tube, a delivery-tube and a
tamping-plug secured thereto, all arranged
substantially as and for the purpose specified.

In testimony that we claim the above we
have hereunto subscribed our names in the
presence of two witnesses.

EGBERT CORNELIUS.
BURT. G. COPE.
